BULLET STOP

Arthur D. Caswell, Anoka, Minn.

Application January 13, 1933, Serial No. 651,508

9 Claims. (Cl. 124—15)

My invention relates to bullet stops and has for its object to provide a simple and compact bullet stop which will be simple in operation and which will function positively and effectively.

5 An object of the invention resides in providing a bullet stop which may be constructed as an individual unit and which may be utilized in conjunction with other units to build up a battery of bullet stops capable of covering any desired area.

10 A still further object of the invention resides in constructing the bullet stop so that additional units may be readily added to the last unit installed as the occasion demands.

15 Another object of the invention resides in constructing the bullet stop in a manner such that the entire area for any desired height may be covered and so that a minimum amount of depth is required in the installation of the invention.

20 An object of the invention resides in providing a bullet stop with a receptacle for bullets disposed within the confines of the stop itself and above the floor level on which the stop is to be installed.

25 A feature of the invention resides in constructing the bullet stop so that access to the receptacle for bullets may be had from the front of the device, thereby making it unnecessary to provide passageways or space to the rear of or below the bullet stop.

30 Another object of the invention resides in constructing the bullet stop with a pair of vertical converging deflector plates arranged to form a throat at their adjacent edges and in further constructing the bullet stop with a baffle behind said throat forming a chamber in which the force of the bullets is spent and forming a conduit for leading the bullets toward the lower end of the chamber.

35 A still further object of the invention resides in providing an inclined floor extending into said chamber and serving to lead the bullets received within said chamber through said throat and forwardly of the bullet stop into a bullet receptacle.

40 Another object of the invention resides in forming an outlet for said chamber at the lower end of said throat through which the bullets are readily discharged into the receptacle.

45 An object of the invention resides in providing a horizontally extending deflector plate disposed between said vertical deflector plates and extending upwardly from the floor toward said throat in a manner to cover said outlet.

50 A feature of the invention resides in providing a rod extending across said vertical deflector plates for supporting said horizontal deflector

plate and in constructing the latter with a flange adapted to engage the rod to hold said horizontal deflector plate in place.

5 An object of the invention resides in providing guards extending into the chamber within the baffle which serve to prevent back splash of fragments of the bullets.

10 A feature of the invention resides in constructing said guards by attaching the baffle to the deflector plates forwardly of the adjacent edges 10 thereof.

15 Other objects of the invention reside in the novel combination and arrangement of parts and in the details of construction hereinafter illustrated and/or described.

15

In the drawings:

Fig. 1 is a perspective view of a bullet stop illustrating an embodiment of my invention and constituting one of the units of a battery.

20 Fig. 2 is a front elevational view of the structure shown in Fig. 1 with the target mechanism removed.

Fig. 3 is an elevational sectional view taken on line 3—3 of Fig. 1.

25 Fig. 4 is a fragmentary plan sectional view taken on line 4—4 of Fig. 2 and drawn to a larger scale.

Fig. 5 is a plan view of a battery of two units such as shown in Fig. 1 with parts of one of the units cut away to illustrate the construction 30 thereof.

35 Fig. 6 is a view similar to Fig. 5 showing the use of the invention with wings.

In the installation of shooting galleries the common procedure in providing a bullet stop has 35 been to install heavy and substantial permanent structures which are more or less built into the building and form a constituent part thereof and by means of which the force of the bullets may be expended. Such construction requires special 40

design of both building and gallery and greatly limits the installation of shooting galleries in previously erected buildings. The present invention provides a simple and inexpensive bullet stop unit which may be combined with other units or with 45 the extension wings usable in conjunction therewith to form a battery of any desired area. Such units are so constructed as to be readily transported and erected and are erected with very little labor requiring no alteration whatsoever of 50 the building in which the shooting gallery is to be installed.

55 My invention proper consists of a number of units such as is shown in Fig. 1. Each of said units being identical in construction, only one 55

of these units will be described in detail. The unit shown in Fig. 1 is indicated in its entirety by the reference character A and consists of two vertically extending deflector plates 10 and 11 arranged in converging relation. The forward edges 12 and 13 of these plates are spaced from one another and are free throughout the entire extent for the purpose of attaching the wings thereto or for the purpose of attachment to adjacent units 10 as will be presently described in detail.

The adjacently positioned edges 14 and 15 of the deflector plates 10 and 11 form a vertically extending throat 16 which is of such dimensions as to admit the flattened bullets to pass therethrough. The two plates 10 and 11 are arranged at such an angle that bullets striking the same will slide along said plates and be discharged from the space between the said plates through the throat 16. The lowermost portion of the bullet stop is provided with a bottom or floor 40 which is constructed to fit in between the two deflector plates 10 and 11. This floor is provided with upwardly turned flanges 17 on which the bullet stop is supported. These flanges are bolted to the deflector plates 10 and 11 through bolts 47. At the upper edges of the two plates 10 and 11 is provided a top 19 similar to floor 40 which is formed with downwardly turned flanges 18 bolted or riveted to the upper edges of the said plates.

Immediately to the rear of the throat 16 is provided a baffle 20 which is constructed from a sheet of metal bent in the form of a spiral. The outer convolution 21 of the spiral is formed with a flange 22 which is bolted to the inner marginal portion 23 of plate 10 by means of countersunk bolts 24. The inner convolution 25 of baffle 20 lies tangent to the rear surface of the marginal portion 26 of plate 11 at 27 and is secured to said plate through a number of clip angles 28. Clip angles 28 are constructed with a leg 29 which are welded or otherwise secured to the baffle 20 and with other legs 30 which lie along plate 11 and are bolted thereto by means of countersunk rivets 31. By means of this construction a vertically extending spiral chamber 32 is provided into which the bullets passing through the throat 16 are received and in which the force of the bullets is expended. The shape of the baffle 20 is such that a bullet leaving the free edge 33 of said baffle strikes the opposite portion 34 of the outer convolution of said baffle at an angle tending to cause the further movement of said bullet inwardly along the spiral. In this manner once the bullet enters the chamber 32 through the throat 16 the entire force of the bullet is expended and the bullet finally dropping downwardly toward the lower end of the chamber 32 which serves as a conduit for conducting the bullets out of the device.

Between the two deflector plates 10 and 11 at the lower portion thereof and between the bottom 40 and a horizontally extending deflector plate 35 disposed between said vertical deflector plate is formed a receptacle 36 into which the bullets collected through conduit 32 are discharged. This receptacle communicates with chamber 32 through an opening 37 in plate 11 at the lowermost portion thereof adjacent throat 16 which constitutes an enlargement of throat 16 and forms a discharge outlet. The floor 40 is bent upwardly to form an incline 39 at the rearward portion thereof below the baffle 20 which extends into chamber 32 and closes the lowermost end thereof. This incline serves to lead the bullets discharged

by the baffle forwardly and into the receptacle 36 formed on the forward part of the floor 40.

The deflector 35 serves as a cover for the receptacle 36 and is removably mounted in its closing position so that access to the receptacle 36 may be had. For this purpose a rod 41 is employed which extends across and is attached to the deflector plates 10 and 11 and supports the plate 35 at its rearward end. A flange 42 formed on this plate engages behind the rod 41 and causes the said plate to remain properly supported in a manner to deflect the bullets striking the same upwardly and away from the opening 37. For this purpose rod 41 is situated toward the rear of the plates 10 and 11 and slightly above the uppermost edge of opening 37.

For the purpose of permitting the discharge of the bullets received within the inner convolutions 25 of the spiral baffle 20 the lowermost portion 43 thereof is severed from the body of the deflector along a line 44 best shown in Fig. 1 and bent outwardly to contact with the forward edge 45 of the deflector plate 11 formed through opening 37. By means of this construction, a clear space is provided at the bottom of the conduit 32 and of a height equal to the height of the opening 37 which freely communicates with the receptacle 36 formed upon the floor 40 and beneath the deflector plate 35. It will readily be comprehended that bullets received within the chamber 32 are discharged upon the incline 39 and slide forwardly into the chamber 32. After a certain number of bullets have been accumulated the deflector plate 35 may be lifted off to uncover receptacle 36 and the bullets removed therefrom. It is to be noted that the receptacle 36 is accessible from the front of the device so that the baffle 20 may be installed close up against the end wall of the building in which the gallery is built. With this construction it is not necessary to employ passageways behind the bullet stop to enable the attendant to collect the bullets or to employ a passageway or special construction beneath the floor of the gallery for like purposes.

In order to prevent back splash or the flying of small fragments of lead from the bullet back through the throat 16 and against the target, a special construction is employed which is best shown in Fig. 4. For this purpose the tangent portion 27 of the inner convolution 25 of the baffle 20 and the salient corner 70 of the outer convolution 21 of said baffle are attached to the two deflector plates 10 and 11 on the rearward sides thereof forwardly of the extreme rearward edges 14 and 15 of the deflector plates. This leaves portions 71 and 72 of the said deflector plates projecting into the chamber 32 which form reentrant acute angles with the said portions of the baffle. These portions form guards for catching small fragments of the bullets which may become broken from the same and prevent the reverse movement of said fragments through the throat 16 and against the target proper.

In Figs. 1 and 3 I have shown a target 48 which may be supported in any desired manner with respect to the bullet stop proper. In these drawings I have shown the target as supported through a carrier 49 mounted on a trolley 50 which rides on a cable 51 stretched between the bullet stop proper and some fixed object at the fixing booth of the gallery. Such construction forming no particular feature of the invention has not been shown in detail. For the purpose of attaching this structure to the bullet

stop proper, a bracket 52 is employed which is bolted to the underside of the top 19 medially of the lateral edges thereof and toward the forward portion of the bullet stop. This bracket 5 is provided with an eye bolt 53 to which cable 54 is attached and is provided with pulleys 55 and 56 over which the usual puller cord 57 passes. This cord is attached to the carrier 49 at 57 and may be operated by the usual handwheel at the 10 firing booth.

In the installation of my invention one or more units such as indicated at A in Fig. 1 may be employed. In Fig. 5 two such units A and B have been illustrated as mounted side by side. 15 When so installed the forward edges 12 and 13 of the adjacent units are brought together and secured through a vertically extending angle 58 which may be bolted to the same. In such case a target 48 is used for each unit and is centrally disposed relative to its bullet stop and mounted in the manner shown in Figs. 1 and 3. With the construction so arranged a minimum depth is required so that no appreciable foreshortening of the gallery is necessary.

20 Where sufficient length is available a number of units C and D may be installed as illustrated in Fig. 6 to cover a greater width and to provide more firing booths for the same number of units. In such installations the units C and D are exactly identical with the units A excepting that the target carrier is not attached to the same. In conjunction with these units, wings 59 and 60 are employed which are attached to the free edges 12 and 13 of the deflector plates 25 10 and 11 and which lie in continuation thereof. For this purpose attaching plates 61 are employed which are bolted both to the marginal portions of these wings and to the marginal portions of the two deflector plates. Supplemental top and floor members 62 and 63 are also employed in such case which are formed with flanges and bolted to the wings 59 and 60 in exactly the same manner as the top 19 and floor 40 46 of the bullet stop proper. The two units with wings attached thereto are arranged with the forwardly disposed edges of the wings 59 and 60 in contact which are secured together through a vertically extending angle 64 similar to the angle 58. With the units constructed and erected 45 as shown in Fig. 6 two targets 65 and 66 may be used for each unit, thereby doubling the number of booths possible with each set of units employed. Where, however, conservation of space in the direction of length is necessary, four units arranged adjacent one another in the manner illustrated in Fig. 5 would be necessary, one target being utilized with each unit.

50 Where the target carrier is installed independently of the units, said units may be placed up against the end wall and need only rest directly upon the ground or floor and need not be attached thereto or braced with respect to the building. Where, however, the target carriers are directly attached to the tops of the 55 units or the extension tops, any suitable bracing may be employed by means of which the units are properly held in position and in a manner to resist the tension applied to the trolley wire or cable supporting the target carrier.

70 My invention is highly advantageous in that an extremely simple and effective bullet stop is provided which is portable and self-containing and which may be quickly and readily installed without appreciable labor and without alteration 75 of the building in which the same is to be used.

The invention is constructed in units which may be built up in any number to form any desired number of booths and to cover any desired area. The units may be built in several heights to fit various story heights. Wings and extension tops and floors may be added to the units to increase the number of targets used with each unit where the available space is to be had. By causing the bullets to be discharged forwardly of the bullet stop, danger to the attendants is entirely prevented since an attendant in removing the bullets would be clearly visible to a person stationed at the firing booth. By means of my improved construction no passageways behind or to the side of the bullet stop is necessary and furthermore no space or mechanism on the floor below for the collection of the bullets is required. The units can be constructed at a nominal cost and of sufficiently strong material to resist repeated firing of any desired caliber of gun. Access to the bullet receptacle is easily had by removal of the closure forming the horizontally extending deflector of the invention. By means of the special construction at the throat of the bullet stop the flying back of small particles of lead from the bullet is prevented and the consequential tearing of the targets entirely eliminated.

Changes in the specific form of my invention, as herein disclosed, may be made within the scope of what is claimed without departing from the spirit of my invention.

Having described my invention, what I claim as new and desire to protect by Letters Patent is:

1. A bullet stop comprising a first vertically disposed deflector plate, a second vertically disposed deflector plate arranged in converging relation with respect to said first deflector plate to form a vertical throat at the adjacent edges of the plates, a spiral baffle behind said throat extending outwardly from said first plate and 35 disposed principally in back of the second plate and forming a chamber in which the force of the bullets is spent and providing a vertically extending passageway, an incline extending into said passageway, said second plate having an opening 40 therein at its lower end and above said incline, said spiral baffle having a portion thereof opposite said opening severed from the major portion thereof and bent to extend up to the portion of said second plate adjacent said opening. 50

2. A bullet stop comprising a pair of vertically disposed deflecting plates arranged in converging relation to form a vertical throat at the adjacent edges of the plates, a baffle behind said throat forming a chamber in which the force of the 55 bullets is spent and providing a vertically extending passageway, a receptacle for bullets at the lower portion of the deflecting plates disposed forwardly of the said chamber and communicating therewith and an inclined deflecting plate disposed between said vertical deflector plates, said inclined deflecting plate directing bullets into said passageway and forming a cover for said receptacle.

3. A bullet stop comprising a pair of vertically disposed deflecting plates arranged in converging relation to form a vertical throat at the adjacent edges of the plates, a baffle behind said throat forming a chamber in which the force of the 65 bullets is spent and providing a vertically extending passageway, a receptacle for bullets at the lower portion of the deflecting plates disposed forwardly of the said chamber and communicating therewith and an inclined deflecting plate disposed between said vertical deflecting 70 plates.

plates, said inclined deflecting plate directing bullets into said passageway and forming a cover for said receptacle, and means for removably securing said inclined deflecting plate in closing 5 position.

4. A bullet stop comprising a pair of vertically disposed deflecting plates arranged in converging relation to form a vertical throat at the adjacent edges of the plates, a baffle behind said 10 throat forming a chamber in which the force of the bullets is spent and providing a vertically disposed passageway, an incline extending into said passageway at the lower portion thereof for directing the spent bullets forwardly therefrom, 15 said throat being formed to provide an enlarged outlet immediately above said incline for the discharge of spent bullets from said passageway, and an inclined deflector shielding said outlet.

5. A bullet stop comprising a pair of vertically 20 disposed deflecting plates arranged in converging relation to form a vertical throat at the adjacent edges of the plates, a baffle behind said throat forming a chamber in which the force of the bullets is spent, and providing a vertically dis- 25 posed passageway, an incline extending into said passageway at the lower portion thereof for di- recting spent bullets forwardly therefrom, said throat being formed to provide an enlarged outlet immediately above said incline for the dis- 30 charge of spent bullets from said passageway, supporting means secured to said plates, and an inclined deflector plate removably carried by said supporting means and shielding said outlet.

6. A bullet stop comprising a pair of vertically 35 disposed deflecting plates arranged in converging relation to form a vertical throat at the adjacent edges of the plates, a baffle behind said throat forming a chamber in which the force of the bullets is spent, and providing a vertically dis- 40 posed passageway, an incline extending into said passageway at the lower portion thereof for di- recting spent bullets forwardly therefrom, said throat being enlarged immediately above said incline to form an outlet for the discharge of spent 45 bullets from said passageway, a rod extending from one deflector plate to the other and at an

elevation above said outlet, and an inclined deflector plate carried by said rod and extending downwardly to the lowermost edges of said first named deflector plates, said last named deflector plate having means thereon for engagement with said rod to hold said plate in position on said rod. 5

7. A bullet stop comprising a pair of vertically disposed deflecting plates arranged in converging relation to form a vertical throat at the adjacent edges thereof, a baffle behind said throat forming 10 a chamber in which the force of the bullets is spent and providing a vertically extending passageway, an incline forming a sloping bottom for said passageway and adapted to direct spent bullets therefrom through the lower portion of 15 said throat forwardly thereof, and a deflector plate inclined upwardly toward the throat for shielding said lower portion of said throat.

3. A bullet stop comprising a pair of vertically 20 disposed deflecting plates arranged in converging relation and having a throat at the angle there- 25 between, a baffle behind said throat forming a chamber in which the force of the bullets enter- ing said throat is spent, said baffle providing a vertically extending passageway, the same having 30 a forward outlet at its lower portion, an incline, forming a sloping bottom for said passageway, adapted to direct spent bullets therefrom forwardly through said outlet, and a deflector in front of and shielding said outlet. 30

9. A bullet stop comprising a pair of vertically disposed deflecting plates arranged in converging relation to form a vertical throat at the adjacent edges thereof, a baffle behind said throat forming a chamber in which the force of the bullets is 35 spent and providing a vertically extending passageway, an incline forming a sloping bottom for said passageway and adapted to direct spent bullets therefrom through said throat forwardly thereof, said throat being enlarged immediately 40 above said incline to facilitate the discharge of the spent bullets from said passageway, and a deflector in front of the throat for shielding said incline and said throat enlargement. 40

ARTHUR D. CASWELL.
